UNITED STATES PATENT OFFICE.

JOSEPH FREDERICK NORMAN, OF LONDON, ENGLAND.

TYPE-CASTING MACHINE.

Application filed November 21, 1925. Serial No. 70,704.

The invention relates to improvements in double-acting type casting machines of the kind described in specification No. 1,165,997. Such machines have hitherto been subject to various disadvantages, which have greatly restricted their use for the following reasons.

It will be readily appreciated that, in order for this kind of machine to give good results, all the moving parts must be very carefully constructed and exactly fitted, particularly those which make up the molds. Moreover, when the molten metal is injected into the mold a considerable quantity of heat must be conducted away before the type can solidify and be ejected from the machine, and the quicker this operation can be effected, the better will be the quality of the product and the speed of production. In the machines previously proposed, the cooling arrangements consisted of a short stationary water cooled top plate carrying a plate forming the upper part of the molds, and a water channel or jacket formed in the bed of the machine and in contact with a stationary plate forming the lower part of the molds, the side portions and slideable matrix ends of the molds being carried between said plates forming the upper and lower mold parts, upon a traveling mold carrier. The channels for the cooling water were concentrated about the place where the molten metal was injected, but the arrangement was found to be of little practical use, because the bottom mold plate became very hot at one point only, and the heat was mainly conducted through the travelling carrier. Consequently the type would not readily solidify and the sliding parts tended to stick fast in their slides, owing to the heat, which could only be remedied by slackening the fit and employing only a few molds on a long carrier and operating the machine at a very slow speed, making it commercially at a serious disadvantage. These drawbacks are moreover not remedied by merely forming each mold complete with movable bottom, sides and top as a single unit, since in addition to the defects above stated, the conduction of heat to the stationary water jackets will be still more difficult.

By the present invention all the above mentioned disadvantages are overcome and a machine is provided which is capable of casting type of high quality with great

rapidity and with little wear upon the moving parts.

According to the invention I provide a type casting machine of the kind above referred to, characterized by a travelling bottom plate for the molds, which plate also forms part of a travelling water jacket. Preferably the water jacket is integral with the travelling mold carrier, through the whole length of which it may extend, and according to a further feature of the invention the water is supplied to the jacket by means of telescopic tubes, secured on the one hand to the travelling mold carrier and on the other hand to the machine bed or other stationary part.

By this means the machine is maintained at a substantially uniform heat throughout, which can be readily controlled within the desired limits by varying the quantity of water passed, and besides giving a high quality product at high speed of production, enables a long mold carrier to be employed carrying any desired number of molds and matrices.

In order that the invention may be clearly understood and readily carried into effect a preferred embodiment of same is illustrated in the accompanying drawings, wherein,

Fig. 1 is elevation of a part of the machine bed carrying the travelling mold carrier, showing three side mold portions mounted in position by way of example. Fig. 2 is a plan. Fig. 3 is a cross section taken on line 3—3 of Fig. 2 to an enlarged scale, and Fig. 4 is an elevation of the complete machine to a reduced scale.

Referring to the drawings, the frame 1 and stationary machine bed 2 (which needs no water jacket) are of usual form and size, and upon the bed is slidably mounted the travelling mold carrier 3. The latter can be of any convenient length, for example considerably longer than the bed 2 (see Fig. 4), and is formed internally with two water channels or jackets 4, 5, which extend throughout practically the whole length of the carrier 3, communicating at one end by passages 6. The channel 4 passes substantially centrally through carrier 3, and below the rear parts of the side mold portions 7, between which slide the matrices (not shown). The other channel 5 lies adjacent the front or casting edge of the mold car-

rier and below the front parts of the side mold portions 7 which actually constitute the sides of the molds, and a plate 8 of hardened steel closes the top of the water channel 5 and forms the bottom or under part of the molds. In order to secure this plate 8 firmly to the carrier 3 so that it forms a water-tight joint and affords an accurate surface which will not warp when heated, the channel 5 has formed therein at short intervals bosses 9, to which the plate 8 is firmly secured by countersunk screws 10, passages 11 being provided in the bosses 9 to permit circulation of the water and serving incidentally to improve the cooling efficiency. Water inlet passages 12 are provided in the carrier 3 communicating with channel 5, and outlet passages 13 communicating with channel 4. Channel 5 may also be lined with a thin copper casing.

The cooling water can be supplied and withdrawn by any suitable means, such as for example by flexible pipes fitted to the carrier 3 and communicating with passages 12, 13, but a much more satisfactory method is by the use of telescopic tubes, as provided according to a further feature of the invention. A bracket 14 carrying tubes 17, 18 is bolted to the carrier 3, conduits 15, 16 in said bracket communicating with said tubes and passages 12, 13. The other ends of said tubes slide in a stuffing box 19 secured to the bed 2. Tubes 20, 21 are connected with the stuffing box 19 and a bracket 22 secured at the opposite end of the bed as shown in Fig. 4, and pipes 23, 24 attached to said tubes respectively supply and lead away the cooling water. Tubes 17, 18 can thus slide telescopically within tubes 21, 20 as the carrier 3 is moved to and fro along the bed, and it will also be apparent that this telescopic movement will assist the circulation of water through the cooling system by alternately drawing water in and forcing it out.

The path of the cooling water may be traced as follows. From inlet pipe 23, through tube 20, tube 18, conduit 16, inlet passages 12, along channel 5 and passages 11, to passages 6, and thence back through channel 4, outlet passages 13, conduit 17, tubes 17, 21 and away by pipe 24.

The casting is effected in known manner by moving the carrier 3 beneath a stationary water cooled upper mold plate and canis as described in specification No. 1,165,997, but it is evident that by providing a travelling bottom mold plate 8 which is cooled

throughout the whole of its length by an attached water jacket, not only is the heat of the molten metal applied at a different point on said plate at each casting operation but a continual supply of cooling water running along said plate rapidly disperses and removes said heat, while at the same time the body of the carrier 3, the matrices and the side mold portions 7 are also cooled. Thus the whole carrier and adjacent parts are maintained at a moderate temperature, the high temperature of casting being only momentary and its effects negligible, the moving parts may be an exact sliding fit without danger of jamming, and the machine is therefore capable of producing type of an exceedingly good quality and at a high speed of production.

I claim:

1. A double-acting type casting machine having a travelling mold carrier, a travelling bottom mold plate secured to said carrier, a travelling water jacket in said carrier in contiguity with said plate, and means for conducting water through said jacket, substantially as and for the purpose set forth.

2. A double-acting type casting machine having a travelling mold carrier, a water channel formed in said carrier, a bottom mold plate secured to said carrier in contiguity with said water channel, and means for conducting water to and from said channel, substantially as described.

3. A double-acting type casting machine having a travelling mold carrier, a travelling bottom mold plate secured to said carrier, a travelling water jacket in said carrier in contiguity with said plate comprising a water channel adjacent one side and a second parallel water channel adjacent the center of the carrier, and means for conducting water to and from said jacket, substantially as described.

4. A double-acting type casting machine having a travelling mold carrier, a travelling bottom mold plate secured to said carrier, a travelling water jacket in said carrier in contiguity with said plate comprising a water channel adjacent one side and a second parallel water channel adjacent the center of the carrier, telescopic water tubes connected between said travelling water jacket and a stationary part of the machine, and means for supplying water to said tubes, substantially as described.

JOSEPH FREDERICK NORMAN.
